UNITED STATES PATENT OFFICE

KARL MUTH, OF DUSSELDORF, GERMANY

CERTIFICATE OR COUPON SHEET FOR USE IN STATISTIC MACHINES

Application filed May 9, 1931, Serial No. 536,295, and in Germany September 3, 1928.

The present invention relates to an improved form of certificate or coupon sheets for use in connection with statistic machines such as for instance Hollerith machines.

The present system of checking or examining coupons or certificates for the approaching payment or redemption of interest dividends or other similar certificates results in great loss of time, and also requires a large staff, and whilst the checking is being conducted mistakes can quite easily be made, and also falsifications or counterfeits are possible.

The usual method adopted for checking or examining such coupons or certificates is as follows:—When the interest coupons or certificates have been issued they are sorted, counted and the maturity date ascertained at the bank, and a similar process has to be gone through by the company, corporation or the like taking over such coupons or certificates, whilst the coupons or certificates presented for redemption after being provided with numbers have to be counted, sorted and placed in numerical order and the maturity date has to be examined and checked. It must be remembered that every coupon or certificate passes through the hands at least seven times, and in many issues the number amounts to hundreds of thousands and in some instances even as much as a million. It will be clearly understood therefore that the method or practice hitherto employed not only necessitates a considerable staff but is also very uneconomical.

A system by which the data of the interest coupons or certificates can be arranged in such a form that a mechanical estimation is possible is already known. In this case, however, it is essential that the form and position at which the standard signs, punchings or perforations are made, correspond in all certificates or coupons. Further, it has been proposed to produce a number of coupons or certificates on one sheet and made detachable from the sheet by perforating the sheet around the edges of the coupons or certificates.

The essential features of the present invention are that the sheet proper, instead of be-

ing perforated around the edges of each coupon or certificate in the ordinary way are provided with uninterrupted slots or cuts extending along each side of each of the coupons or certificates to the proximity of the corners. Interrupted slots are provided across each of the corners of each coupon or certificate, and thus blunting them. The coupons or certificates cohere to the sheet proper only by the interruptions of the slots at the blunted corners, so that when the coupons or certificates are torn off or removed from the sheet proper, they will have perfectly even and clean cut sides, the only unevenness occurring at the blunted corners which is, therefore of no importance. It is important, however, that all the four edges of each coupon should be even and clean cut so that piles or bundles of coupons or certificates can be aligned or evened up effectively.

As the blunted corners of the coupons or certificates do not affect the aligning or evening up of a pile or bundle of coupons or certificates a notch or the like may be punched or stamped out of one or more of the flat corners to assist in aligning or evening up a pile or bundle.

The blunted corners are particularly suitable for this purpose because, as has already been mentioned, the evenness or smoothness of the blunted corners of each coupon or certificate is of little importance.

One particular embodiment of the present invention is illustrated in the accompanying drawings wherein Figure 1 shows an interest certificate or coupon sheet with renewal coupons, and Figure 2 shows a single coupon or certificate on an enlarged scale. In Figure 2 a single interest certificate is shown on a sheet slotted or cut around its edges, and having columns of figures printed on the left hand side, and the text of the certificate printed on the right hand side. The arrangement of the printing on the coupon or certificate may of course vary, and for the purpose of diminution may be imprinted on the back if desired. The sheet is preferably slotted or cut around the edges of the coupon or certificate during the printing thereof.

The coupons or certificates are firmly held

on the sheet proper by means of the interruptions between the slots or cuts at the blunted corners in spite of the long slots around the coupons or certificates. For facilitating and 5 ensuring the correct aligning or evening up of a pile or bundle of coupons or certificates a notch or aperture *a*, preferably U shaped or semi-circular, is provided at the blunted corners. This notch can be made at the same 10 time as the sheet is produced. The interruptions in the corner slots which serve to connect or hold the certificates or coupons to the sheet proper are shown at *b* and the slots or cuts provided along the edges of the coupons 15 or certificates are shown at *c*. The dotted lines on Figure 1 of the drawings mark the position at which the sheet can be folded.

It must be clearly understood that the printing of the coupons or certificates as well 20 as the forming of the slots or cuts and the notches or apertures can all be done in the same operation.

It must be clearly understood also that the invention is also applicable for forming coupons or certificates on stiff blocks instead of 25 sheets of paper.

What I claim and desire to secure by Letters Patent is:—

1. A sheet having detachable portions, and 20 having slits forming a part of the outer edge of each detachable portion, the slits being shaped to form uninterrupted straight sides and ends and also interrupted diagonally cut-off corners to the detachable portions.
2. A sheet having detachable portions of 35 the same size, and having slits forming a part of the outer edge of each detachable portion, and positioning notches, the slits being shaped to form uninterrupted sides and ends 40 and also interrupted diagonally cut-off corners to the detachable portions, the positioning notch of each detachable portion being in the same position in the edge of each detachable portion.
3. A sheet having detachable portions of 45 the same size, and having slits forming a part of the outer edge of each detachable portion, and positioning notches, the slits being shaped to form uninterrupted straight sides 50 and ends and also interrupted diagonally cut-off corners to the detachable portions, the positioning notch of each detachable portion being in the same position in the edge of one of the diagonally cut-off corners of each detachable portion.

In testimony whereof I affix my signature.

KARL MUTH.
